UNITED STATES PATENT OFFICE.

HAROLD F. HAGEN, OF JERSEY CITY, NEW JERSEY, ASSIGNOR TO THE GREEN FUEL ECONOMIZER COMPANY, OF MATTEAWAN, NEW YORK, A CORPORATION OF NEW YORK.

FAN.

1,199,375.

Specification of Letters Patent. Patented Sept. 26, 1916.

Application filed January 13, 1913. Serial No. 741,718.

To all whom it may concern:

Be it known that I, HAROLD F. HAGEN, a citizen of the United States, residing at Jersey City, New Jersey, have invented certain new and useful Improvements in Fans, of which the following is a full, clear, and exact description.

The invention which constitutes the subject matter of this application relates to improvements in fans, compressors, pumps and other kindred apparatuses.

Referring to the drawings: Figure 1 shows a view partly in cross section of one application of my invention. Fig. 2 is a view in side elevation of an impeller blade and the hub upon which it is mounted. Fig. 3 is a front view of the impeller blade and at right angles to the view shown in Fig. 2. Fig. 4 is a top view of the blade and at right angles to the view shown in Fig. 3.

The invention consists essentially in the form of the impeller blades or vanes for imparting motion and energy to the fluid and in the combination of the form of blades and the housing specially designed therefor. The impeller serves to lead the fluid therethrough in accordance with the theory of stream line flow and to direct the fluid from said blades in a substantially conical direction, but the receiver for the fluid may take any desired form, such as a diffuser, or be omitted entirely where it is desired to discharge into large open spaces.

Referring to the drawings in detail the character A represents a shaft upon which the hub B is secured by any suitable means. In the particular construction shown a supporting base C is employed which is provided with a bearing D for the shaft A and also supports the suction ring E. Upon the hub B are located my novel form of blades F the character G designating the path through which the blades are swept when the hub is rotated. To the suction ring E is secured by means of nuts and bolts H the outer wall I of a diffuser. The inner wall K of the diffuser is supported from the outer wall by any suitable means such as strap-iron members L. These walls I and K for ease and cheapness of manufacture are preferably co-axial conical members but it is very obvious that they may be curved in either direction and it is to be understood that I do not limit my invention to this construction as any diffuser which may be said

to be substantially conical may be used. In fact the blades are so designed that they will receive without shock and progressively impart energy to fluid particles traveling in the parabolic stream lines and it is very apparent that if the cost of manufacture be not prohibitive the preferred construction of the walls of the fan, whenever used, would be congruent parabolas. The best efficiencies are attained, however, whenever the walls, whether co-axial conical members or co-axial members curved in the same direction, approach or are inclined toward each other as the radial distance from the axis increases. The shaft A is connected to any suitable motor M which operates the impeller which comprises the hub B and the impeller blades F which are mounted upon said hub.

The hub B and suction ring E constitute what is ordinarily termed the distributor. The curved surface forming the inside of the suction ring and the curved surface of the hub are preferably made tangent to the extreme parabolic stream lines so as to induce a parabolic flow of the fluid particles previous to their entering the impeller. While this is the preferred construction of the hub and suction ring, practical consideration may necessitate the formation of the entrance and suction part of the fan somewhat arbitrarily to suit the different purposes to which the apparatus may be applied.

I will now describe my novel form of blades F which may be used with or without a diffuser and which operate with great efficiency in blowing air into or exhausting air from large open spaces and for other purposes. The first type of blade surface is determined by assuming the air to flow on cones which are arranged between the suction ring and the hub in accordance with the general theory of stream line flow. On these cones are plotted the relative trajectories of the air particles conforming to the principle of an equal amount of energy in the same time with respect to the forward motion of the fluid particles; that is to say, for the purpose of determining the simultaneous positions of the various particles of the fluid only the radial and the axial components of the fluid velocities are considered, or in other words for the determination a section made by a plane through the axis is

the only view necessary and this view is considered to represent the whole 360° or any portion thereof. The second type of blade surface has a constant final angle Θ as described below; the entrance edge is shock free and the exit edge delivering the air from all points with a constant energy content, and the trajectories are plotted to conform to this principle. In either case if a sufficient number of these cones, say 5 or 10, depending upon the size of the fan, are assumed and the correct trajectory drawn on each one a smooth curve may be swept through the points of equal energy. This process gives a blade which is correct throughout its whole extent.

In order to more clearly elucidate the character of my invention I will now discuss the same mathematically. The following equation:

$$\text{Equation 1: } K = Cx - Dr^2$$

is the formula for a parabola where C and D are constants, x the axial distance from an origin and r the radial distance. This equation is arrived at from the underlying principles of the theory of whirl-free stream line motion. By regarding K as a parameter and assigning to it different values the equation may be considered to represent a family of congruent parabolas. Any two of these parabolas may be taken as the limiting walls of the fan which provide a passage free from whirling motion. It can be readily shown from the stream line theory that the time taken by a particle in traveling through this passage is a function of x . By assuming that the energy imparted to this particular particle is also a function of x we get a blade which imparts to every particle an equal amount of energy in the same time. Substituting values in accordance with our equation of stream line flow, and the principle of equal simultaneous energy, in the well known differential equation we have, by integrating the equation, the intersection of the blade surface with the surface of revolution generated by that stream line whose parameter is K , giving

$$\text{Equation 2:}$$

$$\theta = \frac{\phi}{2C(x_1 - x_0)} \left[C(x - x_0) + (K - Cx_0) \log \frac{Cx - K}{Cx_0 - K} \right] - \frac{w}{2D}(x - x_0)$$

This is the equation which I have derived giving the value of angle Θ (as in polar coordinates) of the projection of the intersection above referred to on a plane perpendicular to the shaft or axis. This angle is then plotted with a radial distance r as determined from equation 1 by taking $x =$ to the X used in evaluating this particular angle Θ from equation 1. Projecting the point thus found to a line in what is commonly called the profile view whose abscissa is the same x gives the location of the point in two views.

ϕ is a constant such that $\frac{w\phi}{g}$ is the work done per pound of air; w = angular velocity; g = gravitational acceleration; x_1 = a distance such that $x_1 - x_0$ = a constant and marks the limit of the blade at that point. D and C are constants taken from Equation 1, and K is the arbitrary parameter. By repeating the solution of this equation assigning different values to K the blade surface may be delineated with any required degree of accuracy. It is evident from the congruent nature of the stream lines that these curves may be displaced axially and in addition may be rotated through any angle either individually or collectively. This allows the entrance edge of the blade to be assumed arbitrarily to give a form of blade that may be best adapted to high speeds or other governing conditions. However, the entrance edge of the blade is preferably assumed orthogonal to the stream lines of flow in order that the blade surface may be approximately perpendicular to the direction of the acceleration desired.

The distinctive feature of a blade designed in accordance with the principle of my invention for conical flow is that the angular displacement of the blade increases with an increasing radius; and by angular displacement in this instance I mean the angle as this term is understood in connection with the ordinary polar coördinates of analytical geometry; that is the angle Θ as used in Equation 2. In addition I have devised a modified form of blade using this same equation. Diminishing the value $X_1 - X_0$ decreases the angle Θ and increasing $X_1 - X_0$ increases the angle Θ . For the different curves at different radii as provided for by a change in K different values $X_1 - X_0$ are taken so that the final value of Θ may be substantially constant throughout the whole extent of the blade. It is evident in this case that $X_1 - X_0$ decreases with an increasing K . With this change this blade surface is plotted in the same manner as the former one. This latter form is used for very high speeds, preferably when the constants are such that the required change in $X_1 - X_0$ is comparatively small so that the principle of equal energy in an equal time with respect to the forward motion of the air is approximately adhered to.

Such a fan provided with the design of blades above described may be used for high speeds such as are natural to electric motors or steam turbines, so that the fan may be directly connected to these sources of power and still give low or moderate pressures with a large volume and good efficiency. Furthermore by making the diffuser sufficiently long, so as to recover the rotative energy, these impellers may be used to give high pressures. By mounting two or more

- impellers on the same shaft, with stationary blades of conoidal or cylindrical shape between them or in the suction or delivery passage, still higher pressures may be obtained.
- 5 It is also apparent that an impeller of this type may be advantageously employed in connection with the common spiral housing where it is desirable that the delivery can be connected to a pipe.
- 10 Other uses, other than those mentioned, will obviously be suggested and it is therefore understood that I do not limit myself to those uses above enumerated. Furthermore changes may be made in point of detail and 15 other blades designed in substantial accordance with my invention without departing from its true spirit and scope.

What I claim is:

1. A conical flow fan, comprising a distributor, the inner curved surfaces of which are substantially tangent to the extreme parabolic stream lines of the fluid, in combination with an impeller provided with warped surface blades which impart energy to fluid particles traveling in the said parabolic stream lines, substantially as described.
2. A conical flow fan comprising a distributor, the inner curved surfaces of which are substantially tangent to the extreme parabolic stream lines of the fluid, in combination with an impeller provided with blades, the angular displacement of which relative to the axis of said impeller increases with an increasing radius, substantially as described.
3. A conical flow fan comprising an impeller provided with blades, the angular displacement of which relative to the axis of the impeller increases with an increasing radius, substantially as described.
4. A conical flow fan comprising an impeller provided with blades so shaped that the ratio of the axial distance to the angular displacement relative to the axis of the impeller decreases with an increasing radius.
5. An impeller provided with a blade or vane the acting surface of which is so formed that the lines of intersection of it with a plurality of imaginary cones whose axes coincide with the axis of the impeller, the elements of which lines of intersection are points in the trajectories of air particles moving approximately in the surfaces 55 of the respective cones, are curves prede-
- termined with the radius of curvature of each decreasing in the direction of flow and increasing for corresponding points in the different lines as the distances of said points from the axis increase, said corresponding points being points whose axial distances from the entrance edges of the vanes in which they respectively lie are equal proportions of the total lengths of the lines of intersection in which they respectively lie, 60 said corresponding points being points of equal energy imparted to the air particles and connected by smooth curves, which with the respective trajectories determine the blade surface.
6. A conical flow fan adapted to parabolic stream line flow comprising an impeller provided with blades, the entrance edge of each of which is substantially orthogonal to the stream lines entering the same, the surfaces 65 of said blades being warped to progressively impart energy to and move the fluid particles from the point of entrance thereto to the point of exit therefrom, substantially as described.
7. A conical flow fan comprising an impeller provided with blades the surfaces of which are so curved that the radius of curvature of the intersection of the blade and a cylinder co-axial with the center line of the 75 shaft of the impeller decreases continually from the entrance edge to the delivery edge of the blade whereby energy is progressively imparted to the fluid particles traveling in stream lines and whereby said fluid particles are discharged in the form of a cone 80 from the path of said blades and in stream lines which diverge from the axis of the fan.
8. A conical flow fan comprising an impeller provided with blades the surfaces of 85 which are substantially helical with a pitch that continuously increases axially and continuously decreases radially whereby energy is progressively imparted to the fluid particles and the said fluid particles are 90 moved from a point of entrance thereto to the point of exit therefrom in parabolic stream lines, substantially as described.
- In testimony whereof I affix my signature in the presence of two subscribing witnesses. 105
